DESIGN FOR AN AIRCRAFT TIRE

Charles A. Bigelow, Houston, Tex.

Application November 19, 1945, Serial No. 123,364

Term of patent 14 years

(Cl. D90—20)

To all whom it may concern:

Be it known that I, Charles A. Bigelow, a citizen of the United States, residing at Houston, in the county of Harris and State of Texas, have invented a new, original, and ornamental Design for an Aircraft Tire, of which the following is a specification, reference being had to the accompanying drawing, forming part thereof.

The figure is a perspective view of an aircraft tire, showing my new design.

The characteristic features of my design are represented by the portions shown in full lines.

I claim:

The ornamental design for an aircraft tire, substantially as shown and described.

CHARLES A. BIGELOW.
